CLAIM

I claim the ornamental design for a matchbook, as shown and described.

DESCRIPTION

FIG. 1 is a top, right front perspective view of the matchbook showing my new design;

FIG. 2 is a top, right front perspective view thereof; the cover of the matchbook being partially opened to reveal an insert sheet folded therein;

FIG. 3 is another perspective view thereof; the cover being fully opened and the insert sheet being folded therein;

FIG. 4 is a front perspective view thereof; the cover being fully opened and the insert sheet being unfolded therein;

FIG. 5 is a front elevation view thereof; the cover being fully opened and the insert sheet being unfolded therein;

FIG. 6 is a front elevation view thereof;

FIG. 7 is a back elevation view thereof;

FIG. 8 is a bottom view thereof;

FIG. 9 is a top view thereof; and,

FIG. 10 is a right side view; the left view being a mirror image thereof.

The claimed design is for matchbooks. Various views with the cover being fully or partially opened, and in particular FIGS. 2-5, are used to illustrate the design insofar as the matchbook is capable of such manipulation by consumers. Surface shading is used in the drawings to show contour in the design that otherwise might not be apparent in a particular figure.

The broken line showing of a staple, matches, and a strip of striking material is included for the purpose of illustrating environmental structure and forms no part of the claimed design.
